UNITED STATES PATENT OFFICE.

WILLIAM M. DUNMORE, OF CLAREMONT, NEW HAMPSHIRE.

DOOR OPENING AND CLOSING DEVICE.

Application filed March 24, 1924. Serial No. 701,591.

My invention relates to door opening and closing devices.

It has for its object to provide an improved door opening and closing device and more particularly an improved device of this character adapted to be controlled by an object moving along the passageway which the door controls. A more particular object of my invention is to provide improved door opening and closing mechanism especially adapted to use on garages or the like and whereby the doors may be opened or closed as desired automatically as a machine moves into or out of the garage, my improved mechanism comprising a simple and inexpensive device adapted to be applied to the standard type of door and to be disposed in such manner as to permit free movement of the car. These and other objects and advantages of my invention will hereinafter more fully appear.

In the accompanying drawings I have shown for purposes of illustration one form which my invention may assume in practice.

In these drawings,—

Fig. 1 is a plan view partially in section of a door equipped with my improvement showing the former in closed and open positions.

Fig. 2 is a side elevation partially in section of the same mechanism.

Fig. 3 is an enlarged plan view of the inside operating element.

Fig. 4 is a side elevation of the same partially in section.

Fig. 5 is an enlarged side elevation of the outside operating element, an abutment on a car axle being shown in one position relative thereto.

Fig. 6 is a plan view of the same element.

Fig. 7 is an end elevation of the outside element.

Fig. 8 is a side elevation of the same showing the operative and inoperative positions of its operating member.

In this illustrative construction I have shown my invention applied to a garage, generally indicated 1, having swinging doors 2 and 3 pivoted at their outer edges on vertically disposed pivots or hinges 4 in a usual manner and arranged so that the doors may open outward, operative connections, hereinafter more fully described and including an outside unit 5 and an inside unit 6 adapted to be controlled by a machine, being connected to these doors and operated to cause

the doors to be opened when a machine approaches the same, closed after the machine has entered the garage, opened as the machine moves out of the garage, and closed after the machine has left the garage.

Referring more particularly to these operative connections, it will be noted that each of the doors 2 and 3 is connected to a link or operating member 7 lying flat on the bottom of the garage substantially throughout its length and having an upwardly extending portion 8 pivotally connected at 9 to a suitable bracket on the door. As shown, each of these members 7 also has a bent-up portion 10 on its opposite end pivotally connected as at 11 to the same longitudinally disposed member 12, herein having a rack member 13 attached thereto by suitable means as by bolts 14 and movable longitudinally of a suitable guide or frame 15, suitably fixed in position on the floor of the garage. As illustrated, a pinion 16 journaled at 17 in the frame 15 engages this rack 13 and also a corresponding rack 18 longitudinally slidable in the bottom of the guide 15 and connected at its front end, as at 19, to a rod 20. Herein, this rod 20 also has a depressed portion 21 likewise lying flat on the floor of the garage and connected at its outer end, i. e. at a point outside the doors when closed and suitably spaced therefrom by such a distance as to permit the doors to open freely, with a raised portion 22 which in turn extends longitudinally of a guide 23 generally similar to the guide 15, the front end 24 of the member 20 being freely slidable and guided by this member 23. Herein it will be noted that a normally up-standing operating member 25 is pivoted as 26 in a bifurcated member 27 in turn carried on a member 28 suitably attached to the member 24 as by bolts 29. It will further be noted that this operating member or trip 25 extends a substantial distance above its pivot so that it may be thrown about its pivot by a machine, as for example by engagement with the front axle thereof or with a suitable abutment 30 adapted to be carried by the axle 31 thereof. Herein, the member 30 is suitably attached to that axle by means of bolts 32 and a cooperating clamping plate 33 on the opposite side of the axle from the member 30. Attention is here also directed to the fact that the base of the member 25 is enlarged in opposite directions as shown and that it is supported

at one end on one extremity of a longitudinally extending member 34 attached to suitable cross pins 35 on the guide 23 and disposed longitudinally of the latter. The opposite end of the bottom of the member 25 is in turn seated on the upturned hooked end 36 of a longitudinal spring 37 having an end portion 38 extending around under the front pin 35 and an intermediate portion passing over another transverse pin 39. Further, it will be noted that the rear end of this member 37 is of the same construction as the front end thereof so that the member 25 at either end of the guide 23 may be moved from its upright position shown to an inclined position to permit the abutment 30 to pass by, one of these positions being indicated in dotted lines in Fig. 8. Attention is here also directed to the fact that at the inside end of the rack 13 a bifurcated member 40 similar to the member 28 and pivoted operating member 41 similar to the member 25 is provided, while members 42 and 43 similar to the members 34 and 37 are also provided, the member 41 being adapted to cooperate with the members 42 and 43 as the member 25 cooperates with the members 34 and 37 previously described.

In considering the operation of my improved construction, let us consider that the doors 2 and 3 are closed as illustrated in full lines in Fig. 1 and that the member 25 is in its upstanding position shown in Fig. 5. With the parts in this position it will also be understood that the member 41 will then occupy the position illustrated in Fig. 4. Thus when a car approaches the garage, and its abutment 30 strikes the member 25, that member will be carried inward, sliding over the member 34 in the guide member 23 and carrying the members connected thereto including the member 20 and rack 18 inwardly. As a result of this movement, the pinion 16 will be rotated in a counterclockwise direction in such manner as to feed the rack 13 outwardly and thereby force forward the member 12 and the pivot 11 of the links 7 in such manner as to cause the latter to swing the doors outward from their full line position shown in Fig. 1 to the dotted line position indicated therein. All this will occur before the member 25 reaches a position at the inner end of the guide 23 and the inner ends of the members 34 and 37. As soon as this position is reached, however, continued inward pressure of the abutment 30 against the member 25 will cause that member to be rocked about its pivot and to assume a position, the reverse of but corresponding to the position shown in Fig. 8 wherein the member 25 depresses the end of the spring 37 and thus passes out of the path of the abutment 30. Obviously during this inward movement of the member 25 and the outward movement of the rack 13, the

operating member 21 connected to the latter will be slid from its position shown in Fig. 4 to a corresponding position over the opposite ends of the members 42 and 43. Thus when a car has passed into the garage, the abutment 30 will next engage with the member 41 and cause a similar inward movement of the latter relative to the members 42 and 43 and the guide 15, the rack 13 then moving inward and thus causing the pinion 16 to be rotated in a clockwise direction and the rack 18 to move outwardly. Obviously the movement of the rack 13 will thus cause the links 7 to be operated to close the doors while the movement of the rack 18 will return the member 25 to its outermost position. It will also be apparent that a further inward movement of the car will cause the member 41 to swing about its pivot away from the abutment 30 and thus to permit the car to pass to its desired position in the garage, while the spring 37 will then return the member 41 to its normal or upright position. Conversely, when it is desired to remove a car from the garage, contact of the opposite side of the member 30 with the opposite side of the member 41 will then slide that member outward on the guide 15 and by the resultant movement of the rack 13 and member 12 cause the members 7 to swing the doors open before the car reaches them; the member 41 at the outer end of its travel swinging down out of the path of the abutment 30 as illustrated in Fig. 8. It will also be noted that this outward movement of the rack 13 results in a counterclockwise movement of the pinion 16 and an inward movement of the rack 18 and consequently of the member 25 so that as soon as the car has passed out of the garage its abutment 30 will strike the member 25 and carry it from its innermost position on its guide 23 to its initial position thereon, and, as a result, reverse the operation of the pinion 16 and cause the rack 13 and member 12 to actuate the links 7 to close the doors after the car while the member 41 is simultaneously returned to its initial position. Obviously when the member 25 has reached the limit of its travel it will then be automatically swung down out of the path of the abutment 30, as illustrated in Fig. 8, the car thus being freed when it has closed the garage.

As a result of my improved construction it will be observed that it is possible not only for a car automatically to open and shut the garage doors when approaching a garage and open and close the garage doors when leaving the garage, but also to provide such a mechanism which is so disposed as to provide no impediment to car movement, the whole mechanism being disposed on the floor of the garage and the space in front of the garage in such manner as to enable free car

movement. Attention is also directed to the fact that the mechanism is exceedingly simple and rugged and of a type adapted to be manufactured at small expense. Further, it will be noted that it is adapted to installation in garages of a usual type without changes therein or anything other than a simple pivotal connection of the door swinging links to the doors and fastening of the elements 5 and 6 to the garage floor and the roadway in front of the doors. More particularly, it will be noted that all necessity for digging up the garage floor is obviated, thereby adapting the construction to ready installation at small expense in existing garages. It will also be observed that the disposition of the mechanism on the floor of the passageway is such that no obstacle is placed in the way of the car wheels or the door, the vehicle being thus permitted to enter and leave normally and the door being thus permitted to extend substantially to the plane of the passageway and swing freely, the whole opening and closing mechanism being disposed substantially within the vertical limits of the door and close to the surface of the passageway in substantially a single plane, as distinguished from prior devices requiring substantially larger space vertically either below or above the surface of the passageway. As for the car, it will also be observed that the mechanism required on the car to operate the same is exceedingly simple and readily adapted to be applied thereto. In fact, where the construction of the car permits, no additional attachment to the car is required.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. Door opening and closing mechanism comprising operatively connected door actuating devices disposed on opposite sides of the door in substantially a single plane on the surface of the passageway and each having a reciprocable upstanding operating member engageable for a limited time with an object moving over the passageway and each having operative connections to reciprocate its fellow and to effect a door opening or closing operation.

2. Door opening and closing mechanism comprising operatively connected door actuating devices disposed on opposite sides of the door in substantially a single plane on the surface of the passageway and each having a reciprocable upstanding operating

member engageable for a limited time with a wheeled vehicle at a point between its wheels and each having operative connections to reciprocate its fellow and to effect a door opening or closing operation, said last mentioned connections including a portion in the path of the vehicle wheels substantially in the plane of the passageway.

3. Door opening and closing mechanism comprising operatively connected door actuating devices disposed longitudinally of the center of the passageway in substantially a single plane, said devices including upstanding reciprocable actuating members engageable with a vehicle and releasable therefrom after a limited reciprocation, and door swinging means actuated thereby and having a portion thereof in the path of the vehicle and substantially in the plane of the door bottom.

4. Door opening and closing mechanism comprising alined operatively connected door actuating devices disposed longitudinally of the center of the passage-way inside and outside the door in substantially a single plane and operative by engagement with a wheeled vehicle at a point between its wheels, said devices including upstanding members engageable by said vehicle, and operative connections actuated thereby and disposed substantially within the vertical limits of the door.

5. Door opening and closing mechanism comprising door connected units disposed inside and outside the door on the surface of the passage-way and operated by a moving object moving over the latter including reciprocable operating members and door swinging means reciprocable by either of the latter to swing a plurality of doors.

6. Door opening and closing mechanism comprising door connected units disposed inside and outside the door and operated by a moving object and including a pair of reciprocating operatively connected operating members one of which is connected to the door and both of which are simultaneously movable and in reverse directions upon operation of either.

7. Door opening and closing mechanism comprising door connected units disposed inside and outside the door and operated by a moving object and including a plurality of operating members, one connected to the door and one extending longitudinally beyond the latter member and each successively engageable by said object and operative connections between said members whereby they are simultaneously movable bodily in reverse directions longitudinally of the passageway upon operation of either.

8. Door opening and closing mechanism comprising door connected units disposed inside and outside the door and operated by a moving object including a plurality of op-

- erating members successively engageable by said object, and rack and pinion mechanism operative to produce simultaneous reverse movement thereof.

9. Door opening and closing mechanism comprising door connected units disposed inside and outside the door and operated by a moving object including a plurality of operating members successively engageable by said object, and rack and pinion mechanism connected between said members including a rotatable pinion and a cooperating rack movable with each member.

10. Door opening and closing mechanism comprising operating members inside and outside the door, operated by a moving object as it moves over the passageway, a rack movable bodily with each of the same, a rotatable pinion engaging both racks, and door moving mechanism connected to one rack.

11. Door opening and closing mechanism comprising operating members inside and outside the door as it moves over the passageway, a rack movable bodily with each of the same, a rotatable pinion engaging both racks, and door moving mechanism connected to one rack, said mechanism being disposed on the surface of the passageway.

12. Door opening and closing mechanism comprising operating members inside and outside the door as it moves over the passageway, a rack movable bodily with each of the same, a rotatable pinion engaging both racks, and door moving mechanism connected to one rack, said mechanism including members swinging a plurality of doors.

13. Door opening and closing mechanism including a guide, an operating member movable longitudinally thereof with an object movable over the passageway, and means whereby said member may be depressed by said moving object at one end of its travel.

14. Door opening and closing mechanism including a guide, an operating member movable longitudinally thereof with an object movable over the passageway, and means whereby said member may be depressed by said moving object at either end of its travel.

15. Door opening and closing mechanism including a guide, an operating member movable longitudinally thereof with an object movable over the passageway, and means whereby said member may be depressed by said moving object at one end of its travel including a member supporting spring.

16. Door opening and closing mechanism including a guide, an operating member movable longitudinally thereof with an object movable over the passageway, and means whereby said member may be depressed by said moving object at either end of its travel.

17. Door opening and closing mechanism including a guide, a pivoted operating member movable longitudinally thereof with an object movable over the passageway, and means whereby said member may be depressed by said moving object at either end of its travel including a member supporting spring having its opposite ends engageable by the member.

18. Door opening and closing mechanism comprising guides disposed inside and outside the door, an operating member movable in each guide with an object moving over the passageway, and door operating mechanism connected to one of said members and controlled by the other member.

19. Door opening and closing mechanism comprising guides disposed inside and outside the door, an operating member movable in each guide with an object moving over the passageway, and door operating mechanism connected to one of said members and controlled by a movement of either member.

20. Door opening and closing mechanism comprising guides disposed inside and outside the door, an operating member movable in each guide with an object moving over the passageway, door operating mechanism connected to one of said members, and means whereby movement of either member will operate said mechanism to close the door.

21. Door opening and closing mechanism comprising guides disposed inside and outside the door, an operating member movable in each guide with an object moving over the passageway, door operating mechanism connected to one of said members, and means whereby movement of either member will operate said mechanism to open the door.

22. Door opening and closing mechanism comprising guides disposed inside and outside the door, an operating member movable in each guide with an object moving over the passageway, door operating mechanism connected to one of said members, and means whereby reverse movements of either member will effect reverse movements of the door.

23. Door opening and closing mechanism comprising guides disposed inside and outside the door, an operating member movable in each guide, door operating mechanism connected to one of said members, and means whereby said members are moved simultaneously in opposite directions by a movement of either.

24. Door opening and closing mechanism comprising guides disposed inside and out-

side the door, an operating member movable in each guide and operatively connected to the door, and means whereby after a limited movement in its guide each of said members may be thrown out of operative position therein by the moving object.

25. Door opening and closing mechanism comprising guides disposed inside and outside the door, an operating member movable in each guide and operatively connected to the door, and means whereby after a limited movement in its guide each of said members may be thrown out of operative position therein by a moving object and automatically returned thereto.

26. Door opening and closing mechanism comprising guides disposed inside and outside the door, an operating member movable in each guide and operatively connected to the door and to effect reverse movement of its fellow, and means whereby said members may be successively engaged and moved in said guide by a moving object successively thrown out of operative position in said guide by said object and automatically returned to operative position.

27. Door opening and closing mechanism comprising guides disposed inside and outside the door, an operating member movable in each guide and operatively connected to the door and to effect a reverse movement of its fellow, and means whereby said members may be successively engaged and moved in said guides by a moving object, successively and independently thrown out of operative position in said guides by said object and automatically and independently returned to operative position.

28. Door opening and closing mechanism comprising movable operating members disposed inside and outside the door and engageable by a moving vehicle, door operating mechanism connected to a plurality of swinging doors and reciprocable longitudinally of the center line of the passageway, and operative connections whereby either operating member may be moved by said vehicle to effect reciprocation of said mechanism.

29. Door opening and closing mechanism comprising movable operating members disposed inside and outside the door and engageable by a moving vehicle, door operating mechanism connected to a plurality of swinging doors and reciprocable longitudinally of the center line of the passageway,

and operative connections whereby either operating member may be moved by said vehicle to effect a reverse movement of its fellow and reciprocation of said mechanism.

30. Door opening and closing mechanism comprising movable operating members disposed inside and outside the door and engageable by a moving vehicle, door operating mechanism connected to a plurality of swinging doors and reciprocable longitudinally of the center line of the passageway, and operative connections whereby either operating member may be moved by said vehicle to effect reciprocation of said mechanism, including mechanism whereby said operating member may be disengaged from said vehicle after a predetermined movement therewith and automatically restored to its engageable position.

31. Door opening and closing mechanism comprising movable operating members disposed inside and outside the door and engageable by a moving vehicle, door operating mechanism connected to a plurality of swinging doors and reciprocable longitudinally of the center line of the passageway, and operative connections whereby either operating member may be moved by said vehicle to effect a reverse movement of its fellow and reciprocation of said mechanism, including mechanism whereby either of said members may be disengaged from said vehicle after a predetermined movement therewith and automatically restored to its engageable position.

32. Door opening and closing mechanism comprising movable operating members disposed inside and outside the door and engageable by a moving vehicle, door operating mechanism connected to a plurality of swinging doors and reciprocable longitudinally of the center line of the passageway, and operative connections whereby either operating member may be moved by said vehicle to effect a reverse movement of its fellow and reciprocation of said mechanism, including mechanism whereby either of said members may be disengaged from said vehicle after a predetermined movement therewith and automatically restored to its engageable position, said door operating mechanism being disposed within the doors and operating to open the same outwardly.

In testimony whereof I affix my signature.
WILLIAM M. DUNMORE.

CERTIFICATE OF CORRECTION.

Patent No. 1,658,119.

Granted February 7, 1928, to

WILLIAM M. DUNMORE.

It is hereby certified that error appears in the printed specification of the above numbered patent requiring correction as follows: Page 3, line 114, claim 6, after the word "either" and before the period insert the words "by said movable object"; same page, line 122, claim 7, after the word "object" insert a comma; page 4, line 16, claim 10, after the word "door" strike out the comma and line 124, claim 23, and page 5, line 2, claim 24, after the word "guide" insert the words "with an object moving over the passageway"; same page, lines 23 and 25, claim 26, for the word "guide" read "guides" and lines 23 and 25, same claim, and line 36, claim 27, after the word "object" insert a comma; and that the said Letters Patent should be read with these corrections therein that the same may conform to the record of the case in the Patent Office.

Signed and sealed this 13th day of March, A. D. 1928.

Seal.

**M. J. Moore,
Acting Commissioner of Patents.**
